UNITED STATES PATENT OFFICE.

HALL GOODWIN, OF CHICAGO, ILLINOIS.

FUSE.

Application filed February 8, 1923. Serial No. 535,285.

To all whom it may concern:

Be it known that I, HALL GOODWIN, a citizen of the United States, residing at Chicago, in the county of Cook and State of Illinois, have invented new and useful Improvements in Fuses, of which the following is a specification.

This invention relates to electric fuses in which the fusible element is so held that it can be removed for renewal when it becomes ruptured, and its object is to provide a fuse of this kind which is very simple and inexpensive in construction, the means whereby the fusible element is held being so constructed and arranged that said element is securely held in place, and at the same time, is readily removable for replacement.

The object stated is attained by means of a novel combination and arrangement of parts to be hereinafter described and claimed, and in order that the same may be better understood, reference is had to the accompanying drawing, wherein:

Figure 1 is an elevation of the device; Fig. 2 is a front end view thereof; Fig. 3 is a rear end view of a cap; Fig. 4 is an enlarged central section; Fig. 5 is a view similar to Fig. 4, partly broken away and without a cap, showing certain holding members in another position; Fig. 6 is an end view of the device without the cap, and Fig. 7 is a sectional detail on the line 7-7 of Fig. 5.

Referring specifically to the drawing, the fuse is of that type in which the body has the form of a plug which is adapted to be screwed into a base socket containing the contacts by which the fuse is interposed in the electric circuit to be protected. The body of the plug is shown at 5, the same being formed of a suitable insulating or non-conductive material. The plug body has a chamber 6 opening through one end thereof, and on this end of the plug body is removably mounted a cap 7 carrying at its outer end a glass lens 8 forming a transparent closure for the chamber 6. The other end of the plug body is fitted externally with a sleeve 9 of conductive material, which is formed with helical corrugations to produce the screw threads by which the plug is screwed into the base socket.

In the last-mentioned end of the plug body 5 is centrally embedded a conductor rod 10 having its outer end formed with a head 11 by which connection is made with

one of the contacts interposed in the circuit to be protected. The connection with the other contact is by the way of the sleeve 9 as usual.

At diametrically opposite points, the plug body 5 carries holders for the fusible element, the latter being a strip 12 having an enlargement intermediate its ends containing an inscription denoting the voltage and amperage which the strip is intended to carry. The strip extends across the open chambered end of the plug body 5 so that the inscription is visible through the glass 8, and it can also be readily ascertained whether the strip is intact or has been ruptured, or fused. The glass 8 is set sunken so that if the plug should be dropped the glass is not apt to be fractured as it will not come in contact with the floor or other surface. The glass is molded with the cap 7, the latter being formed of hard rubber or other insulating or non-conductive material. The end of the cap 7 has an internal annular rib 13 which is adapted to seat in a corresponding groove 14 in the edge of the plug body 5 through which the chamber 6 opens. A separable connection between the plug body 5 and the cap 7 is had by forming the interior of the latter with an annular recess 15 in which seat lugs 16 formed on the outside of the plug body at diametrically opposite points. The inner end of the cap has diametrically opposite channels 17 leading to the recess 15. The lugs 16 and the recess 15 are arranged obliquely so that when the cap is given a slight turn a wedging action is produced between the lugs and the walls of the recess, by which the cap is drawn inwardly and its outer end is drawn firmly against the outer edge of the plug body to seat the rib 13 in the groove 14. The cap can be removed from the plug by turning it until the lugs 16 are in line with the channels 17, after which the cap can be readily slipped off, the lugs passing through the channels.

To the inner end of the sleeve 9 is soldered or otherwise rigidly and electrically connected one end of a conductor strip 18 having its other end secured to the plug body 5 by a hook-shaped bend 19 which is engaged across the edge of the open end of the plug body 5, said edge having a notch or recess 20 in which the transverse portion of the bend seats, the extremity of the bend extending into the chamber 6 to

- engage the wall thereof. The strip 18 extends lengthwise of the plug body on the outside thereof, and the latter has a groove 21 in which the strip seats. Intermediate 5 its ends, there is pivoted to the strip 18 a clamping member consisting of a strip 22 of conductive material having at its free end a lateral inward bend 23 forming a jaw for holding one end of the strip 12.
- 10 The strip 22 is positioned to lie closely against the outside of the strip 18 when the jaw 23 is in strip-holding position, and in this position, the jaw is opposite and above the terminal bend 19 of the strip 18 where 15 it extends across the edge of the open end of the plug body, the end of the strip 12 being located between said parts 23 and 18 and securely clamped when the cap 7 is applied, the rib 13 thereof then bearing 20 down on the jaw 23 to hold the same firmly in strip-gripping position.

The pivotal connection of the strip 22 with the strip 18 is made by forming the latter with a longitudinal slot 24 and forming the strip 22 with a terminal loop 25 through which passes a pin 26 extending transversely of the strip and projecting from opposite edges of the looped end, said looped end being reduced in width so that 25 it may seat loosely in the slot 24, with the projecting ends of the pin 26 seating behind the strip 18 on opposite sides of the slot 24. This connection is also a slideable one, and permits a slight play of the strip 30 22 in the direction of its length to enable the jaw 23 to properly engage the end of the strip 12 as hereinbefore described.

The groove 21 is deep enough to leave no part of the strip 22 projecting from the 40 outer surface of the plug body 5 to interfere with the application of the cap 7, and when the latter is in place its interior surface is opposite the strip 22 so that it is now impossible for the latter to swing outwardly to disengage its jaw 23 from the strip 12.

The gripping or clamping means for the other end of the strip 12 are the same as the ones just described, and hence the description need not be repeated, and the same reference numerals with the prefix "a" have been applied thereto in the drawing. However, the strip 18^a is connected to the inner end of the terminal rod 10 where it 55 extends into the chamber 6, said end of the rod carrying nuts 27 between which is clamped a lateral inward bend 18^b of the strip, said bend passing through the side of the chambered portion of the plug body 5.

60 In order to permit the escape of gases from the chamber 6 when the fuse strip 12 blows, the chambered portion 6 of the plug body 5, and the side of the cap 7, have perforations 28.

65 It will be evident from the foregoing that

the fusible strip can be readily removed when it is to be renewed, by merely removing the cap 7 and swinging the holding members 22 and 22^a outwardly, after which the new strip can be applied, and upon 70 swinging the holding members back to holding position, and replacing the cap, the fuse is again ready for use.

I claim:

1. An electric fuse comprising a chambered plug of insulating material, the chamber opening through one end of the plug, a fusible element extending across the outer end of the chamber, conductor members carried by the plug, with which members the 80 ends of the fusible element are in contact, pivoted clamping members carried by the conductor members and engageable with the ends of the fusible member for holding the same in contact with the conductor members, and a cap removably mounted on the end of the plug through which the chamber opens, the interior of said cap engaging the clamping members for maintaining the contact 85 between the conductor members and the ends of the fusible element.

2. An electric fuse comprising a chambered plug of insulating material, the chamber opening through one end of the plug, a fusible element extending across the outer 90 end of the chamber, conductor members extending along the outside of the plug and having terminal portions extending across the end of the plug through which the chamber opens, with which terminal portions the 95 ends of the fusible element are in contact, clamping members pivoted to the conductor members and extending along the outside thereof, said clamping members having terminal portions located above the 100 terminal portions of the conductor members to engage the ends of the fusible element, and a cap removably mounted on the end of the plug through which the chamber opens, the interior of the cap engaging the clamping 105 members and their terminal portions for maintaining the contact between the terminals of the conductor member and the ends of the fusible element.

3. An electric fuse comprising a chambered plug of insulating material, the chamber opening through one end of the plug, a fusible element extending across the outer end of the chamber, conductor members extending along the outside of the plug and having terminal portions extending across the end of the plug through which the chamber opens, with which terminal portions the 115 ends of the fusible element are in contact, clamping members pivoted to the conductor members and extending along the outside thereof, said clamping members having terminal portions located above the 120 terminal portions of the conductor members to engage the ends of the fusible element, and 125 a cap removably mounted on the end of the plug through which the chamber opens, the interior of the cap engaging the clamping members and their terminal portions for maintaining the contact between the terminals of the conductor member and the ends of the fusible element.

130

a cap removably mounted on the end of the plug through which the chamber opens, the interior of the cap having a rib engageable with the terminal portions of the clamping members for maintaining the contact between the terminals of the conductor member and the ends of the fusible element.

4. An electric fuse comprising a chambered plug of insulating material, the chamber opening through one end of the plug, a fusible element extending across the outer end of the chamber, conductor members extending along the outside of the plug and having terminal portions extending across the end of the plug through which the chamber opens, with which terminal portions the ends of the fusible element are in contact, clamping members pivoted to the conductor members and extending along the outside thereof, said clamping members having terminal portions located above the terminal portions of the conductor members to engage the ends of the fusible element, and a cap removably mounted on the end of the plug through which the chamber opens, the interior of the cap having an annular rib and the outer edge of the chamber having a groove in which the rib is adapted to seat, said rib being also engageable with the terminal portions of the clamping members

for maintaining the contact between the terminals of the conductor member and the ends of the fusible element.

5. An electric fuse comprising a chambered plug of insulating material, the chamber opening through one end of the plug, a fusible element extending across the outer end of the chamber, conductor members extending along the outside of the plug and having terminal portions extending across the end of the plug through which the chamber opens, with which terminal portions the ends of the fusible element are in contact, clamping members having pivoted and sliding connections with the conductor members and extending along the outside thereof, said clamping members having terminal portions located above the terminal portions of the conductor members to engage the ends of the fusible element, and a cap removably mounted on the end of the plug through which the chamber opens, the interior of the cap engaging the clamping members and their terminal portions for maintaining the contact between the terminals of the conductor member and the ends of the fusible element.

In testimony whereof I affix my signature.

HALL GOODWIN.
